UNITED STATES PATENT OFFICE

EDWIN H. POWERS, OF SAGINAW, MICHIGAN

PISTON AND METHOD OF MAKING THE SAME

Application filed April 2, 1926. Serial No. 99,387.

The present invention appertains to improvements in pistons, in the art of which many efforts have been made heretofore by which to reduce their weight as well as their cost of production.

In the main, these are the special objects of the improvements hereinafter set forth, these ends being attained not only by a novel construction embodying a composite body of cast and sheet materials, but also by a novel method of drawing or stamping and molding which shows material economy in manufacturing costs with a superiority of the product.

15 To this end the present invention is characterized as to novelty by the provision of a piston body which is composed of a head of cast metal and a skirt of drawn or die-stamped light sheet metal, said skirt being 20 built of corresponding cylindrical portions which when conjoined form complementary parts providing an interiorly reinforced section or body with which the cast head peculiarly coacts to afford a distribution of the 25 explosion stresses to be transferred to the connecting rod.

Secondly, an important feature resides in the provision of a skirt so constructed that the reinforcement referred to takes the form 30 of complementary sections serving as wrist pin bearings, the general similarity of the sections of said skirt portion requiring a minimum number of dies with the resultant material saving in stamping operations.

35 Other objects and advantages of the invention will be hereinafter set forth and the novel features thereof defined by the appended claims.

40 In the accompanying drawings:

Figure 1 is a side elevation, partly in section, of a piston body constructed in accordance with my invention;

Figure 2 is a vertical sectional view on the plane indicated by the line 2—2 of Figure 1;

45 Figure 3 is a bottom plan view, showing more clearly the rectangular opening accommodating the connecting rod;

Figure 4 is a sectional view on the line 4—4 of Figure 1 showing in plan the lower portion 50 of the piston skirt;

Figure 5 is a side elevation of the skirt unit after the sections have been conjoined and previous to turning in of the end flanges;

Figure 6 is a top plan view of the part shown in Figure 5; and

55 Figure 7 is a side elevation of the skirt unit, after the end flanges have been turned in and ready to receive the die casting, a portion being broken away and shown in section.

Like reference characters designate corresponding parts throughout the several figures 60 of the drawing.

Referring to the drawings, the piston construction of this invention embodies the head portion 1 in which the ring grooves 2 are 65 formed, and the skirt portion 3, the former being of cast material and the latter of sheet material.

I am aware that composite pistons of this 70 general type are not broadly new and I shall therefore point out hereinafter the distinguishing features of these improvements as well as their advantages.

In the first place, the skirt portion 3 is 75 composed of two sections which correspond in every particular excepting only as to their length dimension, the lower section preferably being equal to the length of the upper section plus the head 1. The reason for this variation will be apparent to those skilled in 80 the art to which this invention relates but in the main it gives rise to an equalization of the lateral pressures by virtue of the disposition of the wrist pin bearings centrally of the piston body.

85 For either of these skirt sections, therefore, the blank sheet metal is first drawn up into a cylindrical piston body, having a closed end, said closed end being then depressed by the die at opposite sides to produce semi-cylindrical depressions 4, while the material is pierced or cut away centrally of the end to provide a rectangular opening 5 of a size sufficient to accommodate movements of the connecting rod. The edges of this opening 90 are bent inwardly forming an annular flange 6 which greatly strengthens the metal against deformation. Two such sections, one slightly longer than the other, as before stated, are 95 now placed end to end as shown in Figures 5 100 and 7.

and 7 and spot welded preferably at the points designated 7, as shown in Figure 6, the cylindrical depressions 4 now registering with each other to form the complementary 5 portions of the wrist pin openings. The cylindrical unit or body thus formed is now arc-welded around the abutting joint as indicated at 8 so as to obtain an integral skirt portion. Following this the flanges 9 at the 10 opposite ends of the skirt unit are turned inwardly, thereby providing at these points the proper resistance to deforming stresses.

The skirt is thus prepared for the casting of the head 1 which, it will be apparent from 15 Figures 1 and 2, is interlocked with the top or short section of the skirt by the end flange 9 thereof. In this operation the mold is so formed as to provide the opposite interior extensions 10 of the head which extend over 20 and abut the upper bearing sectors 4. Such an arrangement, it will be obvious, is important for the taking care of the explosion stresses, relieving the side walls of the skirt to a great extent.

25 The piston head 1 may now be machined and the bushings 11 pressed into place, following which the usual grinding of the piston is effected.

It will be apparent from the foregoing that 30 the conjoined ends of the skirt sections act in the nature of a bracing web which gives to the body of the piston adequate strength for all purposes and I desire it to be particularly understood that I believe I am the first to form 35 a piston body by conjoining two corresponding sections in the manner hereinbefore set forth. The piston so constructed will necessarily be very light and will possess many other advantages which are well known in 40 connection with composite piston constructions.

Having thus described my invention, what I claim as new and desire to secure by Letters Patent of the United States is:—

45 1. A composite piston comprising a cylindrical sheet metal body provided with a transverse web, said web having depressions at opposite sides of the body to form wrist pin bearings and reinforcing means, and a cast 50 head having interlocking connection with an end of the body, said head being provided with extensions coacting with the said bearings.

55 2. A composite piston comprising a skirt portion of sheet material and a head of cast material, said skirt portion being composed of two cylindrical sections having partially closed ends, said ends forming a transverse web shaped to receive a wrist pin and having 60 a flanged opening therein which constitutes a connecting rod opening having flanged edges.

65 3. A composite piston comprising a cylindrical sheet metal body formed with a transverse web and opposite wrist pin bearings,

and a cast head interlocked with said body and having an inwardly disposed extension engaging the opposite wrist pin bearings of one section.

4. A composite piston comprising a cylindrical sheet metal body formed of complementary matching sections with wrist pin bearing elements, and a head carried by said body interlocked with the body and coacting with the bearing elements to reinforce the 70 latter.

In testimony whereof I affix my signature.
EDWIN H. POWERS.
